UNITED STATES PATENT OFFICE.

JOSEPH VALIBILE, OF MANITOWOC, WISCONSIN.

HOISTING MECHANISM FOR MIXING-MACHINES.

1,145,279.

Specification of Letters Patent. Patented July 6, 1915.

Application filed September 3, 1912. Serial No. 718,430.

To all whom it may concern:

Be it known that I, JOSEPH VALIBILE, a citizen of the United States, residing at Manitowoc in the county of Manitowoc and 5 State of Wisconsin, have invented certain new and useful Improvements in Hoisting Mechanism for Mixing-Machines, of which the following is a specification, reference being had to the accompanying drawings.

10 This invention relates to new and useful improvements in mixers and more particularly to concrete mixers.

The primary object of the present invention is to provide a mixer drum which is 15 provided with mechanism for rotating the drum and also for raising and lowering the same when the ingredients to be mixed are emptied therein, or discharged therefrom.

A further object of the present invention 20 is to provide a portable frame having a mixing drum mounted within an auxiliary frame pivotally mounted to the said portable frame, and means whereby the drum will be rotated and means for raising and 25 lowering the auxiliary frame so that when the ingredients to be mixed are applied within the drum, they will be thoroughly commingled together when in a raised position and be discharged from the drum when 30 in a lowered position.

Other objects will appear hereinafter as the description proceeds.

With the above and other objects in view, this invention consists of the novel details 35 of construction, combination, formation and arrangement of parts as will be hereinafter more fully described and particularly pointed out in the accompanying drawings, in which—

40 Figure 1 is a side elevation embodying my invention as applied to a portable truck. Fig. 2 is a plan view of the same. Fig. 3 is a longitudinal section through the same taken on the line 3—3 of Fig. 2. Fig. 4 is 45 a transverse section taken on the line 4—4 of Fig. 1, and Fig. 5 is an enlarged front elevation of the same.

Reference now being had to the accompanying drawings wherein corresponding 50 parts are designated by like numerals throughout the several views, the numeral 10 indicates the body of an ordinary portable truck being supported by ground wheels 11 and having secured to its front 55 end the usual draft appliance 12.

Mounted upon the rear end of the framework of the truck is a supplemental frame which has mounted thereon my improved mixing machine. This supplemental frame comprises a forward supporting member, indicated by the numeral 13, and a rear supporting member 14, each of which being connected adjacent their upper extremities by means of diagonally extending brace rods 15.

Vertically extending supports 16 are mounted adjacent the member 13 of the supporting frame and are connected by a transverse member 17 upon which is journaled within bearing boxes 18, a transversely extending drive shaft 19. One end of this shaft 19 has keyed thereto a belt pulley 20 which is adapted to be connected with a suitable source of power by means of a belt 21, whereas the opposite end of this shaft 19 is provided with a sprocket wheel 22. Journaled within the bearings mounted within the member 13 of the supplemental frame, is a transversely extending shaft 23. This shaft is slidably mounted within the 75 bearings 24 formed within the member 13, and one end thereof is squared, as at 25 and projects laterally beyond the supplemental frame. This projection 25, of the shaft 23, is supported by means of a bracket 26 and 80 has mounted thereon a sprocket wheel 27, which is connected to the sprocket wheel 22 by means of a sprocket chain 28.

Pivotedly mounted, as at 29, upon the shaft 19, are a pair of parallel extending 90 arms 30 of an auxiliary frame which has rotatably mounted therein, the mixing drum 31. The outer or free ends of these arms 30 are provided with lateral extensions 32, which are adapted to operate within segmental slots 33 formed within the vertically extending side members of the frame 14.

The drum 31 comprises two sections, one of which, indicated by the numeral 34, is substantially cylindrical and has connected thereto a frustum section 35. The front end of this drum being open, whereas the rear end thereof is closed by means of a plate 36.

Secured adjacent the rear ends of the 105 arms 30 is a cross bar 38 which has extending therefrom a pair of spaced bearings 40 journaled upon the shaft 19. To provide means for supporting the drum upon the arms 30, I provide a pair of vertically ex- 110

tending supports 41 which are permanently mounted upon each of the arms 30 and are connected by the substantially semi-circular brace bars 42. These brace bars 42 have rotatably mounted therein flanged rollers 43. Secured upon the periphery of the drum adjacent the medial portion thereof is a track 45 upon which the flanged rollers 43 are adapted to travel, thereby providing means for supporting the forward end of the drum which will also limit its longitudinal movement and provide means whereby the same may be freely rotated.

A thrust bearing 46 is secured upon the outer face of the plate 36 by means of set screws or the like, and has detachably mounted therein a shaft 47'. This shaft 47' is supported within a suitable bearing 48' mounted upon the member 38 and has keyed to its free end a beveled gear 49'. This beveled gear 49' is adapted to mesh with the beveled gear 50' keyed upon the shaft 19, as shown, so that as power is applied to the said shaft, it will also impart a rotary motion to the drum.

The diagonally extending cross bars 15 are preferably channeled so as to provide guideways 47 in which is adapted to reciprocate a block 48. Secured to this block 48 are a pair of cables 49 which extend from pulleys 50 formed upon the end face of the transverse member of the support 14 and the lower end of these cables are connected to the arms 30. Journaled within the transverse member of the support 13 is a shaft 51, having keyed to one end thereof a beveled gear 52 which is adapted to mesh with beveled gears 53 and 54, respectively, keyed upon the slidable shaft 23. The opposite end of this shaft 51 is provided with a screw 55 which is adapted to operate within a bearing 56 formed within the central portion of the block 48.

It is obvious from the foregoing description that when power is applied to the shaft 19 it will impart a rotary motion to the drum, thereby thoroughly mixing the ingredients emptied therein and at the same time will operate the slidable shaft 23 and by sliding this shaft 23 by means of a handle 57, till the beveled gear 53 comes in mesh with the beveled gear 52, it will operate the shaft 51 which will obviously raise the auxiliary frame in which the drum is mounted by the mechanism before described, but when the beveled gear 54 is in mesh with the beveled gear 52, it will reverse its movement, thereby causing the outer end of the

drum to descend through the mechanism, as previously described.

Mounted within the inner periphery of the drum are a plurality of longitudinal spirally extending blades 58 which are preferably angular-shaped in cross section and extend the full length of the drum. It is obvious when the drum is in a raised position through the mechanism before described, the blades 58 will direct the ingredients emptied therein and within the frustum portion of the drum, thereby thoroughly mixing the same, but when the drum is lowered through the mechanism as before described, the blades 58 will direct the ingredients to the opening end of the drum, whereby the same may be emptied in a suitable receptacle.

It will be manifest from the foregoing that the description taken in connection with the accompanying drawings, that I have provided a drum which will be strong, durable and efficient in use, and which will greatly reduce the present cost of manufacture of such devices, thereby making them commercially desirable, and it is to be further noted that other minor details of construction may be resorted to that come within the scope of the present invention without departing from the spirit thereof.

What I claim is:—

A framework having therein longitudinally extending parallel channeled side bars forming guide-ways and disposed on a predetermined incline, a transversely extending bar having its extremities movable along said guide-ways, guide members carried by said framework adjacent the upper extremities of the guide-ways, an auxiliary frame rotatably supported by the frame-work and movable about a horizontal pivot, flexible members passing over the guide members and secured at one of their ends to said bar at points opposite the longitudinal center thereof and at their opposite ends to the auxiliary frame, a longitudinally disposed threaded shaft working through said bar at substantially its longitudinal center and in threaded engagement therewith, a bearing carried by the framework in which said shaft is journaled, and means for rotating the shaft in opposite directions.

In testimony whereof I hereunto affix my signature in the presence of two witnesses.

JOSEPH VALIBILE.
